BALANCE BLOCK FOR BUILDINGS

Jacob F. J. Bakker, Lakewood, Ohio

Application August 31, 1933, Serial No. 687,656

8 Claims. (Cl. 72—77)

My invention particularly relates to balance blocks which may be incorporated in building structures to insure non-injury to such structures, particularly large buildings, by reason of earth tremors such as are occasioned by earthquakes. Essentially the invention comprises blocks of a particular construction mounted adjacently above and upon the building foundation and adjacently beneath the building superstructure and capable of absorbing the horizontal movements of the foundation occasioned by the earth tremors during an earthquake without communicating these horizontal movements to the superstructure.

The annexed drawings and the following description set forth in detail certain means embodying my invention, such means disclosing, however, but a few of the various forms in which the principle of the invention may be applied.

In said annexed drawings:

Figure 1 is an elevation, partly in vertical section, of the corner of a building with which is incorporated one set of my improved balance blocks;

Figure 2 is a fragmentary view of elements similar to those shown in Figure 1, illustrating modified means for securing the lower balance block to the building foundation;

Figure 3 is an elevation, partly in vertical section, showing a modified form of balance block, also showing an electrically actuated device and wiring diagram adaptable for giving notice of any horizontal movements of the building superstructure, this view also suggesting the positioning of the balance blocks beneath an interior column of the building superstructure;

Figure 4 is a view, upon an enlarged scale, of the balance block feature of the elements shown in Figure 1 and the building elements immediately adjacent thereto, this view showing the several elements during the normal position thereof;

Figure 5 is a plan section, taken in the plane indicated by the line 5—5, Figure 4;

Figure 6 is a view of the elements shown in Figure 4 in the several positions thereof when an earth tremor has moved the building foundation horizontally laterally of its regular position; and

Figure 7 is a fragmentary view of the balance blocks as shown in Figure 4, illustrating a modified form of structure serving as a grease-retaining and protection shield.

Referring to the annexed drawings in which the same parts are illustrated by the same several numbers in the different views, and particularly referring to the structure shown in Figures 1, 4, 5 and 6, a building superstructure 1 of any

suitable standard design is provided with a floor beam or sill 2 beneath one end of which, and for purposes of illustration, at a corner of the building, are disposed my improved balance blocks consisting of an upper bearing member 3 suitably rigidly secured to the sill 2 and a lower bearing member 4 suitably rigidly secured to the building foundation 10. The upper and lower bearing blocks 3 and 4 are formed with opposed inner concave surfaces 5 and 6, respectively, which form a pocket 7 within which is positioned a bearing ball 8 adapted, in conjunction with a suitable number of other like bearing balls positioned at intervals in like sets of bearing members around the foundation 10, to support the weight of the superstructure 1. It will be noted that the balls 8 are of such a size as to somewhat space, one from the other, the upper and lower bearing members 3 and 4. It will also be noticed that the horizontal dimensions of the pocket 7 are materially larger than the diameter of the ball 8 so that lateral enlargements 9 of the pocket 7 are provided into which the ball 8, as hereinafter fully explained, may roll upon the bearing surfaces 5 and 6.

In the form of invention shown in Figures 1, 4, 5 and 6, the space between the contiguous end parts of the bearing members 3 and 4 is in part filled by a bearing plate 11 having a central hole 12 of a diameter substantially equal to that of the ball 8 so that the latter is fitted within said hole with a close sliding fit which does not interfere with the rolling movement of the ball upon the surfaces 5 and 6. The balance of the vertical space between the contiguous end portions of the bearing members 3 and 4 is filled by a ring of bearing balls 14 which rest in, and are adapted to roll in, and in part extend from, an annular ball race 13 formed in the periphery of the upper part of the lower bearing member 4.

Referring particularly to Figures 4 and 6, it will be evident that upon the lateral movement of the foundation 10, due to earth tremors, the bearing block 4 will be moved correspondingly and hence the ball 8 will be rolled upon the surface 6 so as to climb such surface in a direction opposite to that which the foundation 10 moves, although actually the ball 8 will be moved to a greater or less extent in the same direction as the movement of the foundation 10. Also, the bearing plate 11 will be moved by and to the same extent and in the same direction as the ball 8, the movement of the plate 11 being facilitated by the series of bearing balls 14 which act as rollers. Furthermore, the ball 8 will roll upon the upper

bearing surface 5 in a direction corresponding to that of the movement of the foundation 10. However, the upper bearing member 3 which is rigidly secured to the superstructure 1 will not be moved except slightly vertically, this vertical movement being due to the travel of the ball 8 from its two-point contact with those opposed points of the bearing surfaces 5 and 6 most widely spaced to a two-point contact with said surfaces less widely spaced. In the illustration shown in Figures 4 and 6, the capacity for relative movement of the several parts is shown and it is presumed that the foundation 10 has been moved by the earth tremor somewhat to the left of its normal position, such as illustrated by the normal position in Figure 4 and the shifted position in Figure 6; that the ball 8 has traveled upwardly upon the right hand side of the lower bearing surface 6 and downwardly upon the left hand side of the upper bearing surface 5, thus compensating for the left hand movement of the foundation 10 without inducing a corresponding movement in the upper bearing member 3 secured to the superstructure 1, the latter being unaffected except for the slight vertical movement thereof, clearly shown in Figure 6. During the relative horizontal movements of the bearing blocks 3 and 4 and the consequent slight vertical movement of the upper bearing block 3 and the superstructure mounted thereon, the series of bearing balls 14 are not subject to the weight of the building but act only as rollers for the movement of the bearing plate 11 and the large ball 8.

In order to facilitate the easy movement of the ball 8 and the series of balls 14, the pocket 1 is filled with grease, and a flexible shield 16 is secured by one of its edges to the upper bearing member 3 and by the other edge to the lower bearing member 4 to serve as a grease-retaining member and to prevent the entrance of dirt between the meeting surfaces of the balance block members.

In Figure 7, I illustrate a modified form of shield, which consists of two continuous circular members 17 and 18, both of which are secured in a dirt-excluding manner to the respective upper and lower surfaces of the bearing plate 11 and also respectively secured, one to the upper bearing member 3 and the other to the lower bearing member 4.

In Figure 3, I illustrate a modified structure for the lower bearing member. In this form of structure, this lower bearing member comprises two complementary sections 19 and 20 formed respectively with concave and convex surfaces to accommodate a series of balls 23 positioned in the ball race 22 formed by said opposed concave and convex surfaces. The balls 23 completely fill a circular field whose diameter is that comprehended by the series of balls 23 shown in Figure 3. In this form of device, the lower bearing member section 19 is a concavo-convex member, of which the concave face serves for the bearing surface of the large ball 8 and the convex face serves as one side of the ball race for the series of balls 23. A compound action of the balance blocks of the form shown in Figure 3 results from an earth tremor which laterally moves the foundation 10 in that a part of said foundation movement is communicated through the base plate 21, the bearing member section 20, the balls 23 and the bearing member section 19 to the comparatively large central ball 8, and a part is absorbed by

the adjustment of the lower bearing member section 20 upon the field of balls 23.

Referring further to the modification shown in Figure 3, I therein illustrate how my improved balance blocks are adaptable for use under any column in any part of the building, the base plate 24 of said Figure 3 being a base for an interior column to which and adjacently beneath which is secured the upper bearing member 3 of the balance blocks.

The lower bearing member 4 of my improved balance blocks may be secured to the foundation 10 in any appropriate desired manner. In Figure 1, I have shown the securing thereof to reinforcing beams contained within the concrete foundation 15 10, and in Figure 2 I show the securing of the lower bearing member by anchor bolts 26 to a plain concrete foundation, a base plate 25 being interposed between said concrete foundation and the lower bearing member 4.

In order that minor earth vibrations may be absorbed, I interpose material between the superstructure and the upper bearing member 3, and between the foundation 10 and the lower bearing member 4, which is capable of absorbing slight tendencies of the lower bearing member 4 to move laterally and of the superstructure 1 to move vertically, such as the paper liners 27, clearly indicated in Figures 4 and 6.

I provide means for indicating the earth tremors, as shown by the movements of the foundation 10, and for indicating any sidewise movements of the superstructure 1, if perchance the intensity of the earth tremor is such that all of the sidewise movement of the foundation 10 is 35 not absorbed by the balance blocks. The indicator for the foundation movements is suggested in Figure 4, and the indicator for the sidewise movements of the superstructure 1 forms a part of Figure 3. These indicator means 40 form no part of the invention claimed in this application.

Referring first to the indicator for the lateral foundation movements, Figure 4, I provide spring contact plates 28 secured to, and at spaced points 45 around, the lower bearing member 4, and extended upwardly so as to intersect the path of the periphery of the bearing plate 11, when the relation of said plate and the lower bearing member 4 is changed, due to the lateral movements 50 of the foundation 10 and the lower bearing member 4. These plates 28 are electrically connected to short conductors 28', adaptable for connection to a main conductor and other suitable signal mechanism (not shown).

Referring particularly to the electrical device for signalling the sidewise movements, if any, of the superstructure 1, I provide a circuit 32, Figure 3, which includes a battery 38 and an alarm 39 and is connected at its ends respectively 60 to the floor sill 2 and to a terminal 34 of a housing mounted upon the floor sill 2 and having an insulating exterior wall, such as the glass wall 35, which is secured at its upper end within a flange 34' of the top terminal 34 and at its lower 65 end in a lower terminal 33 by which the housing is mounted upon the floor sill 2. An upwardly extended wire spring 36 is mounted in the base member 33 in contact with the floor sill 2 and extends adjacently near the upper terminal 34 70 but is spaced somewhat therefrom. The spring 36 is closely wound and preferably is provided with a slight amount of initial tension. If the floor sill 2 and hence the superstructure 1 of the building partakes to any appreciable extent of the 75

sidewise movements of the foundation 10 induced by the earth tremor, the spring 36 will vibrate laterally and contact the inside face of the flange 34' of the terminal 34 and close the circuit, thus causing the alarm 39 to give audible notice of the sidewise movement of the building super-structure.

What I claim is:

1. Balance blocks for buildings comprising bearing members having opposed concave segments forming an interior ball pocket, a ball mounted in the pocket in rolling contact with the segments, the pocket being larger than the ball in horizontal dimensions to permit relative movements of the bearing members and relative movements of the latter and the ball, one of the bearing members being formed with a ball race encircling its pocket segment, a series of balls in said race, a plate supported by one face upon said series of balls and having its opposite face in contact with the other bearing member in the normal position of the bearing members, said plate being movable with, and to the same extent, as, the first-mentioned ball.
  2. Balance blocks for buildings comprising bearing members having opposed concave segments forming an interior ball pocket, a ball mounted in the pocket in rolling contact with the segments, the pocket being larger than the ball in horizontal dimensions to permit relative movements of the bearing members and relative movements of the latter and the ball, one of the bearing members being formed with a ball race encircling its pocket segment, a series of balls in said race, a plate supported by one face upon said series of balls and having its opposite face in contact with the other bearing member in the normal position of the bearing members, the plate being annular and the first-mentioned ball being symmetrically positioned within the annulus of the plate with a free rolling fit therewith.
  3. Balance blocks for buildings comprising bearing members having opposed concave segments forming an interior ball pocket, a ball mounted in the pocket in rolling contact with the segments, the pocket being larger than the ball in horizontal dimensions to permit relative movements of the bearing members and relative movements of the latter and the ball, one of the bearing members being formed with a ball race encircling its pocket segment, a series of balls in said race subject to the weight of the other bearing member in the normal position of the bearing members, said series of balls being movable relatively to said other bearing member, bearing means connected to said first-mentioned ball and resting upon said series of balls, and a flexible outer protective and grease-retaining shield connected to the bearing members and covering the space therebetween.
  4. Balance blocks for buildings comprising bearing members having opposed concave segments forming an interior ball pocket, a ball mounted in the pocket in rolling contact with the segments, the pocket being larger than the ball in horizontal dimensions to permit relative movements of the bearing members and relative movements of the latter and the ball, one of the bearing members consisting of two spaced sections

forming a ball-race therebetween, and a series of balls in the ball-race.

5. A building structure comprising a super-
structure and a foundation, bearing members
secured respectively to the superstructure and
the foundation and having opposed concave seg-
ments forming an interior ball pocket, vibration-
dampening means interposed between the super-
structure and the foundation and their respective
bearing members, a ball mounted in said pocket 10
in rolling contact with the segments, the pocket
being larger than the ball in horizontal dimen-
sions to permit relative movements of the bearing
members and relative movements of the latter
and the ball, one of the bearing members being 15
formed with a ball race encircling its pocket seg-
ment, a series of balls in said race subject to the
weight of the other bearing member in the normal
position of the bearing members, said series of
balls being movable relatively to said other bear- 20
ing member, and bearing means connected to
said first-mentioned ball and resting upon said
series of balls.

6. Balance blocks for buildings comprising bearing members having opposed concave segments forming an interior ball pocket, a ball mounted in the pocket in rolling contact with the segments, the pocket being larger than the ball in horizontal dimensions to permit relative movements of the bearing members and relative movements of the latter and the ball, one of the bearing members being formed with a ball race encircling its pocket segment, a series of balls in said race, and bearing means contacting the other bearing member in the normal position of the bearing members, said means being connected to said first-mentioned ball and movable upon said series of balls during the relative movements of the bearing members, said series of balls acting as rollers for said means. 10 25 30 35 40

7. Balance blocks for buildings comprising bearing members having opposed concave segments forming an interior ball pocket, a ball mounted in the pocket in rolling contact with the segments, the pocket being larger than the ball in horizontal dimensions to permit relative movements of the bearing members and relative movements of the latter and the ball, one of the bearing members being formed with a ball race encircling its pocket segment, a series of balls in said race, a plate supported by one face upon said series of balls and having its opposite face in contact with the other bearing member in the normal position of the bearing members. 40

8. Balance blocks for buildings comprising 55
bearing members having opposed concave seg-
ments forming an interior ball pocket, a ball
mounted in the pocket in rolling contact with the
segments, the pocket being larger than the ball
in horizontal dimensions to permit relative move-
ments of the bearing members and relative move-
ments of the latter and the ball, means forming 60
rollers mounted upon one of said bearing mem-
bers exteriorly of the pocket segment thereof,
and a bearing plate connected to said ball and 65
supported by said rollers and subject to the
weight of the other bearing member in the normal
position of the bearing members.
